U.S. Cl. D90—20

FIG. 1

FIG. 2

FIG. 1 is a perspective view of a tire showing the new design, it being understood that the opposite side of the tire is substantially like the side shown;

FIG. 2 is a fragmentary transverse sectional view through the tire.

The dominant features of our design reside in the portions shown in full lines.

We claim:

The ornamental design for a tire, substantially as shown and described.
